UNITED STATES PATENT OFFICE.

EDMUND W. ZEH, OF NEWARK, NEW JERSEY.

TITLE-STACKING MACHINE.

Application filed July 21, 1922. Serial No. 576,469.

To all whom it may concern:

Be it known that I, EDMUND W. ZEH, a citizen of the United States, and a resident of Newark, in the county of Essex and State of New Jersey, have invented new and useful Improvements in Tile-Stacking Machines, of which the following is a specification.

This invention relates in general to machines for handling tile and more particularly to a machine for expediting the removal of tile from the press forming the same.

Heretofore it has been impossible for an operator to remove tile from a tile press as rapidly as the tile can be produced. A slow and inefficient operation of the press has thus resulted from the inability of the tile removing operator to keep pace with the press when the same is operated at full capacity.

The primary object of my invention is to provide semi-automatic means for collecting or stacking the tile produced in a plurality of operations so that the press may be continuously and efficiently operated at its full capacity.

Another object of the invention is to provide a machine of this character which can be readily attached to a tile press or the like and is so formed as to permit the tile to be slid from said press to itself as the press operator charges the press with a new supply of "dust," said machine having means for arranging said tile in rows and being constructed to stack or arrange in superposed layers the tile produced in a plurality of operations of the press.

Further objects of the invention are to provide a machine of the character described comprising a substantially horizontal guideway adapted to receive a plurality of tile and having a portion of its bottom displaceable or removable to permit the tile thereon to fall by gravity beneath the same, and a vertically movable table arranged beneath said displaceable portion of the guideway to receive said tile falling therefrom; to provide in such a machine means automatically actuated by movement of said displaceable portion of the guideway upon movement thereof to lower said table to permit stacking of said tile on said table beneath said guideway, and to obtain other results and advantages as may be brought out by the following description.

Referring to the accompanying drawings, in which like numerals of reference indicate the same parts throughout the several views,

Figure 1 is a top plan view of a tile stacking machine embodying my invention, showing the same used in connection with a well-known type of tile press;

Figure 2 is a transverse vertical sectional view through the machine taken on the line 2—2 of Fig. 1;

Figure 3 is a side elevation of the tile stacking machine;

Figure 4 is a vertical longitudinal sectional view through the machine taken on the line 4—4 of Fig. 2;

Figure 5 is a fragmentary transverse sectional view through the guideway in the machine and the tile supporting table showing the table partially loaded with stacked tile;

Figure 6 is a detached perspective view of the movable portion or shutter of the bottom of the guideway, and

Figure 7 is a detached perspective view of the removable plate carried by the table.

For the purpose of illustrating the principles of my invention I have shown the tile stacking machine used in connection with a well-known type of tile press for producing tile, comprising a base portion A, a lower die member B and an upper die member C reciprocable on guides D mounted in the base to cooperate with the lower die in forming the tile.

The tile stacking machine comprises a frame including a base 1 having a pair of spaced and parallel arms 2 projecting therefrom and connected at their outer ends by a tubular cross-piece 3 in which is journaled a shaft 4, the said cross-piece serving to reinforce the arms 2 and provide with the base 1 a rigid frame. A pair of vertical frame pieces 5 are arranged in spaced relation transversely of the arms 2 and support at their upper ends a guideway for receiving tile.

The said guideway comprises spaced and parallel side pieces 6 extending longitudinally of the frame and secured to the upper ends of the transverse frame pieces 5 in any suitable manner as by means of screws 7. The guideway is provided with a bottom formed in two sections 8 and 9, one of which is stationary and the other of which is movable or displaceable. Said sections are preferably mounted in grooves 60 formed on the

inner faces of the side pieces 6, and are preferably of the same length so as to support the same number of tile. An end piece 10 is secured to the side pieces 6 at the end of 5 the guideway carrying the movable bottom section, said end piece permitting the movable bottom section of the guideway to slide beneath it and limiting movement of the tile with said movable section in one direction 10 longitudinally of the guideway. The said bottom sections 8 and 9 are arranged in the same plane so that their upper surfaces form continuations of each other, and the movable section, in the present instance the section 15 9, is provided with a handle 11 at its outer end whereby said section may be slid longitudinally of the guideway. A plurality of partitions 12 extend longitudinally of the guideway above the bottom thereof 20 so as to form passages for a plurality of rows of the tile 13 as clearly indicated in Figure 1.

A vertically movable table 14 is arranged beneath the movable section 9 of the guideway and is mounted at opposite sides thereof on rack bars 15 vertically movable in bearings 16 formed on the arms 2 of the frame and provided with movable cover plates 17 for closing the bearings and holding the rack bars against lateral movement 30 therein.

The shaft 4 is provided adjacent its ends with pinions 18 which mesh with the respective rack bars 15 to actuate the table 35 14. One end of the shaft 4 has fixedly mounted thereon a ratchet wheel 20 engaged by a spring pawl 21 pivotally mounted at 22 on a ratchet disk 23 rotatably mounted on the said shaft and engaged by pawls 24 40 and 25 of an escapement mechanism for controlling rotation of the shaft 4. The said pawls 24 and 25 are rigidly mounted in spaced relation at one end of a lever 26 pivotally mounted intermediate its ends, as at 45 27, to the cover plate 17 of one of the bearings 16 for one of the rack bars 15. The end of the lever 26 opposite the pawls 24 and 25 projects vertically upward to a point adjacent the side pieces 6 of the guideway 50 and is provided with an opening 28 to slidably receive a rod 29 carried by the movable section 9 of the bottom of the guideway. The action of gravity on the table 14 tends to rotate the shaft 4 in the direction indicated by the arrow on Figure 3, but one of the pawls 24 or 25 is normally in engagement with the ratchet disk 23 to hold the shaft against such rotation. The rod 29 is provided at opposite sides of the lever 26 with 55 adjustable abutments 30 and 31 so that when the movable section 9 of the guideway is moved in one direction the abutment 30 engages the lever 26 and oscillates the same in one direction to release the pawl 24 from 60 the ratchet disk 23 and when said movable section 9 is moved in the opposite direction the abutment 31 engages the lever 26 to release the pawl 25 from the ratchet disk 23. In this operation, one of the pawls 24 or 25 releases the ratchet disk 23 to permit rotation of the shaft 4 and the other of said pawls engages the said ratchet disk to stop 70 said rotation of the shaft. The relation of the pawls 24 and 25 with the ratchet disk 23 and the pinions 18 and rack bars 15 is preferably such that the table 14 descends a distance equal to substantially one-half the thickness of the tile upon each movement of the lever 26; and the table is initially positioned a distance below the movable section 9 of the bottom of the guideway a distance greater than one-half the thickness of one of the tile. To adjust this relative position of the table and the bottom of the guideway, the rack bars 15 may be provided at their ends with adjustable collars 32 carrying set screws 33 to engage the ends of the respective bearings 16 of the rack bars. The top of the table 14 is preferably in the form of a removable plate 34 provided with a handle 35.

When the tile stacking machine is to be used in connection with a tile press, the frame 1 is secured to the base of the press so that the bottom of the guideway 6 is substantially flush with the top of the lower die member B of the press when the same is in discharging position. A number of the partitions 12 are utilized to divide the guideway into a number of passages equal to the number of rows of tile formed by the press. As the tile are ejected from the press by the "dust" box, as described in my co-pending application Serial No. 418, 891, they are pushed onto the guideway 6 as shown in Figures 1 and 4. The first batch of tile so ejected from the press will cover the fixed section 8 of the bottom of the guideway, and the next batch of tile discharged from the press will move the said first-mentioned batch onto the movable or displaceable section 9 of the bottom of the guideway. The said movable section is then pulled outwardly from the guideway by the operator grasping the handle 11, as indicated in dotted lines on Figure 4, and the tile on the said section will then fall by gravity onto the plate 35 on the table 14, movement of the tile with the movable section of the bottom being prevented by the end piece 10. When the said movable section is pulled to its outward limit the adjustable abutment 31 actuates the lever 26 in one direction so that the table 14 is permitted to drop a distance equal to one-half the thickness of the tile, and when the movable section of the bottom is returned to its normal position the abutment 30 actuates the lever 26 in the opposite direction to permit the table 14 to again drop a dis-

tance equal to one-half of the thickness of the tile. This operation is performed each time a batch of tile is positioned on the movable section 9 of the guideway, and each 5 batch of tile is thus deposited upon the next preceding batch so as to stack the tile or arrange them in superposed layers. The tops of the uppermost tile are always spaced from the bottom of the guideway as the 10 movable section 9 is pushed back to its normal position, so that there is no danger of the said movable section injuring the tile. It will be obvious that the capacity of the table 14 may be varied as desired, but in 15 the present instance the table is adapted to support ten layers of tile each including forty-eight tile. In other words, the table supports forty-eight stacks each including ten tile. After the table is filled to its 20 capacity, the operator removes the plate 34 with the tile thereon and conveys the tile to the next desired place. The table 14 is then returned to its normal position, and for this purpose I may provide the shaft 25 4 with a hand wheel or lever 36. To elevate the table it is thus merely necessary to rotate the hand wheel in a direction opposite to that shown in Figure 3, the pawl 21 slipping over the teeth of the ratchet 20, so that the ratchet disk 23 is not moved.

With my invention it will be understood that the tile press can be rapidly and efficiently operated to produce a large number of batches of tile without stopping, and 35 with an operator always present to operate the movable section 9 of the bottom of the guideway and another operator disposing of the preceding stacks of tile, the operation of the machine can be substantially 40 continuous.

While I have shown and described a tile stacking machine embodying certain details of construction, it will be understood that this is only for the purpose of illustrating the principles of the invention and 45 that the invention may be utilized for stacking or handling other articles and objects. Also, many modifications and changes can be made in the construction of the machine 50 without departing from the spirit or scope of the invention, and therefore, I do not wish to be understood as restricting myself except as required by the following claims when construed in the light of the 55 prior art.

Having thus described the invention, what I claim is:

1. A machine of the character described including a substantially horizontal manually reciprocal displaceable support to receive an object so that when said support is displaced said object falls by gravity therefrom, a vertically movable second support arranged beneath said first-mentioned support to receive said object as it falls from

said first-mentioned support and movable away from said first-mentioned support by action of gravity, means for normally holding said second support against movement, and means operated by said displaceable support upon movement thereof to actuate said holding means and permit said second-mentioned support to move away from said displaceable support. 70

2. A machine of the character described including a manually displaceable support to temporarily receive an object so that when said support is displaced said object falls by gravity therefrom, a second support beneath said first-mentioned support to receive said object as it falls, and means operated by said first-mentioned support upon movement thereof for moving said second-mentioned support after said object has been deposited thereon to permit another object to fall from 80 said first-mentioned support to said second-mentioned support. 85

3. A machine of the character described including a substantially horizontal guideway to receive a plurality of objects and having a fixed portion and a manually displaceable portion, said displaceable portion being adapted to successively receive said objects from said fixed portion and permit them to fall by gravity from said guideway 90 as said displaceable portion is displaced, a vertically movable table arranged beneath said displaceable portion to receive said objects as they fall from said displaceable portion, and means operated by said displaceable portion upon movement thereof for moving said table away from said displaceable portion of the guideway after each deposit of objects upon said table to permit succeeding objects to fall upon the next preceding object in stacked relation. 100 105

4. A machine of the character described including a substantially horizontal guideway to receive an object and having a portion of its bottom manually horizontally 110 displaceable so that as said portion is displaced an object thereon falls by gravity therefrom, a vertically movable table arranged beneath said displaceable portion to receive said object as it falls, and means operated by said displaceable portion upon movement thereof for moving said table downwardly away from said displaceable portion a distance substantially equal to the thickness of said object upon each complete 115 operation of said displaceable portion. 120

5. A machine of the character described including a substantially horizontal guideway to receive an object and having a portion of its bottom manually horizontally displaceable so that as said portion is displaced an object thereon falls by gravity therefrom, a table arranged beneath said displaceable portion to receive said object as it falls, said table being vertically movable away from 125 130

said displaceable portion by action of gravity, escapement means for normally holding said table against descent, and means operated by said displaceable portion upon movement thereof to actuate said escapement means to permit descent of said table after the object falls upon said table.

6. A machine of the character described including a frame, a substantially horizontal guideway mounted thereon to receive an object and having a portion of its bottom displaceable so that as the same is displaced an object thereon falls therefrom by gravity, a table arranged beneath said displaceable portion to receive said object as it falls from said guideway, a vertically movable rack bar supporting said table, a shaft mounted in said frame and carrying a pinion meshing with said bar, said table tending to descend and rotate said shaft by action of gravity, and escapement means for normally holding said shaft against rotation.

7. A machine of the character described including a frame, a substantially horizontal guideway mounted thereon to receive an object and having a portion of its bottom displaceable so that as the same is displaced an object thereon falls therefrom by gravity, a table arranged beneath said displaceable portion to receive said object as it falls from said guideway, a vertically movable rack bar supporting said table, a shaft mounted in said frame and carrying a pinion meshing with said bar, said table tending to descend and rotate said shaft by action of gravity, and escapement means actuated by operation of said displaceable portion of the bottom of the guideway for normally holding said shaft against rotation and permitting rotation thereof to allow descent of said table after an object has been deposited thereon.

8. A machine of the character described including a substantially horizontal reciprocating displaceable support to receive an object so that when said support is displaced said object falls by gravity therefrom, a table arranged beneath said support to receive said object as it falls from said support, a vertically movable rack bar for supporting and permitting movement of said table away from said support by action of gravity, a pinion meshing with said rack bar, pawl and ratchet escapement means for normally holding said pinion against rotation to prevent descent of said table, and means operated by said displaceable support upon movement thereof to actuate said escapement means and permit descent of said table.

9. A machine of the character described including a substantially horizontal reciprocating displaceable support to receive an object so that when said support is displaced said object falls by gravity therefrom, a

table arranged beneath said support to receive said object as it falls from said support, a vertically movable rack bar for supporting and permitting movement of said table away from said support by action of gravity, a pinion meshing with said rack bar, a ratchet fixedly connected to said pinion, a pawl engaging said ratchet to normally hold said pinion against rotation, and means operated by said displaceable support to actuate said pawl and permit rotation of said pinion.

10. A machine of the character described including a substantially horizontal reciprocating displaceable support to receive an object so that when said support is displaced said object falls by gravity therefrom, a table arranged beneath said support to receive said object as it falls from said support, a vertically movable rack bar for supporting and permitting movement of said table away from said support by action of gravity, a pinion meshing with said rack bar, pawl and ratchet escapement means for normally holding said pinion against rotation to prevent descent of said table, and means carried by said displaceable support to operate said escapement means upon movement of said support in each direction to permit descent of said table step by step a distance to permit a second object to be deposited upon said first-mentioned object in stacked relation.

11. A machine of the character described including a substantially horizontal reciprocating displaceable support to receive an object so that when said support is displaced said object falls by gravity therefrom, a table arranged beneath said support to receive said object as it falls from said support, a vertically movable rack bar for supporting and permitting movement of said table away from said support by action of gravity, a pinion meshing with said rack bar, a ratchet fixedly connected to said pinion, a lever carrying two pawls adapted to alternately engage and disengage said ratchet upon oscillation of the lever to permit descent of said table step by step, and means carried by said displaceable support to swing said lever alternately in opposite directions in accordance with the movement of said support.

12. The combination with a tile press, of a tile stacking machine comprising a frame provided with a substantially horizontal guideway having a portion of its bottom fixed and another portion of its bottom manually displaceable, said fixed portion being adapted to receive a batch of tile directly from said press and said displaceable portion being adapted to receive said batch of tile from said fixed portion as the next batch is discharged from said press, said displaceable portion permitting said tile to

fall therefrom by gravity when it is displaced, a vertically movable table arranged beneath said displaceable portion to receive said tile as they fall from said displaceable portion, and means operated synchronously with said displaceable portion to cause descent of said table away from said displaceable portion after said tile fall thereon and permit succeeding batches of tile to fall upon the next preceding batch in stacked relation.

13. The combination with a tile press, of a tile stacking machine comprising a frame provided with a substantially horizontal guideway having a portion of its bottom fixed and another portion of its bottom manually displaceable, said fixed portion being adapted to receive a batch of tile directly from said press and said displaceable

portion being adapted to receive said batch of tile from said fixed portion as the next batch is discharged from said press, said displaceable portion permitting said tile to fall therefrom by gravity when it is displaced, a vertically movable table arranged beneath said displaceable portion to receive said tile as they fall from said displaceable portion, said table being mounted to descend by action of gravity, escapement means for normally holding said table against descent and arranged to permit such descent step-by-step to receive successive batches of tile upon the next preceding batches in stacked relation, and means operated by said displaceable portion upon movement thereof to actuate said escapement means to permit descent of said table.

EDMUND W. ZEH.
